UNITED STATES PATENT OFFICE

172,442

WATCH

André Richter, Geneva, Switzerland

Application July 12, 1952, Serial No. 20,599

In Switzerland (international application)
May 28, 1952

Term of patent 7 years

(Cl. D42—8)

To all whom it may concern:

Be it known that I, André Richter, a citizen of no country, residing at Geneva, Switzerland, have invented a new, original, and ornamental Design for a Watch, of which the following is a specification, reference being had to the accompanying drawing, forming part thereof.

In the drawing:

Fig. 1 is a plan view of a watch showing my new design,

Fig. 2 is a side elevational view thereof.

I claim:

The ornamental design for a watch, substantially as shown.
